UNITED STATES PATENT OFFICE

2,618,886

BUBBLE BLOWER

Ludwig W. Wagner, Los Angeles, Calif.

Application June 19, 1946, Serial No. 677,719

3 Claims. (Cl. 46—7)

1

This invention relates to a bubble blower, and its principal object is to provide a simple and attractive bubble blower which will be very amusing to children. Another object is to provide a bubble blower having an attached container for the bubble forming fluid, and having also a film holding ring attached to the blowing tube, the latter being connected to the container by a connection whereby the ring may be dipped into the fluid in the container to pick up a film from the fluid.

Another object is the provision of a container and a resilient connection which may be detached from the tube, whereby the tube and ring may be manipulated separately from the container, as a bubble maker.

Another object is to provide a saddle adjustably secured to the tube and having curled side edges for detachably securing the ring and resilient connection to the saddle.

With these and other objects and advantages in view, this invention consists in the several novel features hereinafter fully set forth, and more particularly defined in the appended claims.

The invention is clearly illustrated in the drawing accompanying this specification, in which:

Fig. 1 is a side elevation partly broken out of a bubble blower, embodying a simple form of the present invention;

Fig. 2 is a plan thereof;

Fig. 3 is a perspective view of the saddle and a reinforcement member, and a fragment of the resilient connection showing these parts disconnected from each other;

Fig. 4 is a perspective view of the ring;

Fig. 5 is a cross-section taken on the line 5—5 of Fig. 1; and

Fig. 6 is a cross-section taken on the line 6—6 of Fig. 1.

Referring to said drawing, which is merely illustrative of one embodiment of the invention, the reference character 8 designates a blowing tube having a mouth-piece 9 secured to one end. To the tube is secured a saddle 10 which comprises a flat elongated strip 11, the end portions of which are made wider than the intermediate portion, and are formed with curled side edges 12, 13. The intermediate portion of the strip is curled to form a socket portion 14, in which the discharge end of the tube 8 is adjustably held.

Secured in the curled edges 12, 13 of the saddle is a metal strip 15, which reinforces the saddle whereby to prevent it from being bent out of shape.

Secured in the curled edges 12 of the saddle are

2

the arm extensions 16 of a ring or loop 17. The ends of the ring or loop 17 are brought together as seen in Figs. 2 and 4, and are extended therefrom substantially at right angles thereto to form arms 18, and said arms 18 are bent at an angle thereto, as seen in Figs. 1 and 4, to form arm extensions 16, which are inserted into the grooves formed by the curled edges 12. If desired, said arm extensions 16 may be rigidly fastened to the curled edges as by welding them thereto.

The ring or loop 17 is set at an angle to the tube 8, and its upper end is disposed slightly above the longitudinal axis of the tube, so that puffs of air forced through the tube will pass through the ring or loop slightly below its upper edge and strike the film at a point adjacent its upper edge, which increases the efficiency of the device. Associated with the tube 8 is a shallow container 19 for containing a suitable bubble-forming fluid, and said container is connected to the saddle by a connection which permits the ring or loop to be dipped into the fluid contained in the container, whereby a thin film of the fluid is carried away by the ring or loop 17 when lifted up from the fluid.

In the form of connection illustrated herein, a resilient strip of flat metal is provided, which is bent into a substantially U shape, one end of which is secured to the container as by welding it to the lower side thereof. The other end of the resilient connection 20 is made slightly narrower than the main portion thereof to provide a tab 21, which may be inserted into the grooves formed by the curled edges 13, whereby to secure the connection 20 to the tube.

In use the device is held between the first two fingers and the thumb of a person's hand, and the ring or loop is dipped into the container by contracting the U bend of the connection 20, as is clearly seen by the dotted lines in Fig. 1. The U bend is then permitted to expand, bringing the tube (see Fig. 1) into a substantially horizontal position. The user blows through the mouthpiece 9, sending a blast or blasts of air against the film carried by the ring or loop 17, and forming bubbles which become detached from the remainder of the film of fluid and float into the air. When the film carried by the ring or loop has been used up, the ring or loop may again be dipped into the fluid in the container. It will be observed that any excess fluid carried up by the ring or loop drips into the container and is not lost, nor is it spilled upon the floor, furniture or other objects.

If desired, the container, together with its connection 20, may be detached from the saddle and

the tube and ring may be used in the conventional manner of dipping the ring into a receptacle containing bubble forming fluid, and then waving the tube, together with its ring, through the air or blowing through the tube. For convenience the tube, saddle and ring may be termed a bubble blower.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. A bubble blower, comprising a tube, a saddle member adjustably connected to said tube and formed at its ends with curled side edges, said tube being adjustable lengthwise of said saddle, a ring formed with arms held by said curled edges at one end of the saddle, and the plane of the ring disposed at an angle to the tube beyond one end thereof, a shallow container for bubble forming fluid, and a resilient U shaped connection secured at one end to the container, with its other end removably secured to the edges at the other end of the saddle, said resilient connection when contracted functioning to dip the ring into fluid contained in the container.

2. A bubble blower, comprising a tube, a saddle member secured to said tube and formed at its ends with curled side edges, a ring formed with arms held by said curled edges at one end of the saddle, with the plane of the ring disposed at an angle to the tube beyond one end thereof, a container for bubble forming fluid, and a resilient U shaped connection extending between and connected at its respective ends to the container and

the curled edges at the other end of the saddle, said connection being removably secured to said saddle whereby the tube, saddle and ring may be detached from the resilient connection and used separately therefrom.

3. A bubble blower, comprising a tube, a saddle member having a socket in which the tube is adjustably secured, said saddle being formed at its ends with curled side edges, a ring formed with arms held by said curled edges at one end of the saddle, with the plane of the ring disposed at an angle to the tube beyond one end thereof, a container for bubble forming fluid, and a resilient U shaped connection extending between and connected at its respective ends to the container and the curled edges at the other end of the saddle, said connection being removably secured to said saddle whereby the tube, saddle and ring may be detached from the resilient connection and used separately therefrom.

LUDWIG W. WAGNER.
